UNITED STATES PATENT OFFICE.

CLIFFORD R. WASSELL, OF CHICAGO, ILLINOIS, ASSIGNOR TO CONLON ELECTRIC WASHER COMPANY, INC., OF CHICAGO, ILLINOIS, A CORPORATION OF NEW YORK.

ELECTRIC HEATING ELEMENT.

1,253,915.

Specification of Letters Patent. Patented Jan. 15, 1918.

Application filed May 3, 1916. Serial No. 95,012.

To all whom it may concern:

Be it known that I, CLIFFORD R. WASSELL, a citizen of the United States, residing at Chicago, in the county of Cook and State of Illinois, have invented a certain new and useful Improvement in Electric Heating Elements, of which the following is a full, clear, concise, and exact description, reference being had to the accompanying drawings, forming a part of this specification.

My invention relates to electric heating devices and is concerned with the provision of an improved heating element to the end of simplicity, low cost of manufacture, and efficiency.

According to my invention I provide a structure in which the resistance wire, of such material as nichrome or chromel, is suspended "aerially" in a grid, thereby avoiding the necessity of covering the wire and entailing the advantage of distributing the heating influence directly over the desired area.

The arrangement which I provide also lends itself effectively toward a circuit arrangement whereby either one or both of two heating elements may be connected in circuit. Important among the advantages of my invention is the particular means whereby the resistance wire is supported, to the end of simplicity in assembling the entire structure.

In the accompanying drawings,

Figure 1 is an elevational view of the structure of my invention;

Fig. 2 is a sectional view taken on the plane of the line 2, 2, of Fig. 1, and looking in the direction indicated by the arrows;

Fig. 3 is a sectional view taken on the plane of the line 3, 3, of Fig. 1, and looking in the direction indicated by the arrows;

Fig. 4 is a sectional view taken on the plane of the line 4, 4, of Fig. 1, and looking in the direction indicated by the arrows;

Fig. 5 is a perspective view of one of the supporting members; and

Fig. 6 is a perspective view of one of the spacing members.

The grid is in the form of a rectangular frame 7 having the spider arms 8, 8. Each of these spider arms is made desirably of sheet metal and is in channel formation, as illustrated in Figs. 3 and 4. Within each of these spider arms there are disposed two strips 9, 9, of insulating material, these strips being

laid face to face, as shown, and after insertion in the channel, held in place by clamping over the extensions 11, 11, of the sheet material, as illustrated. One of these insulating strips 9 is slotted at proper intervals upwardly from the bottom, while the other strip is slotted downwardly from the top at the same intervals, these slots being illustrated at 10. These slots are of such depth that when the two strips are laid together they overlap leaving a continuous opening 12 through which the resistance wire 13 may pass. This is the structure of each of the spider arms.

It will now be seen that in assembling the structure the spider arms are all made ready for the reception of the insulating strips and the insulating strips which are slotted downwardly from the top are disposed in place. The resistance wire or wires are then laid in these slots and after the resistance wire or wires have been all properly arranged, the other set of insulating strips 9, those slotted upwardly from the bottom, are put in place, being slipped over the resistance wires, as illustrated. After the two strips have thus been brought in complete face to face register, they fully occupy the channel in which they are disposed and the extensions 11, 11, hereinbefore referred to, are clamped over to complete the structure.

The resistance wires 13, 13 remain uncovered and therefore full efficiency is secured, the grid being properly mounted in an oven or other adaptable place. With this arrangement, it will be seen that the resistance wires may be distributed over a considerable area in perfect safety and with ample protection. I preferably arrange the resistance wire or wires in convolution and in the present form I have shown a double strand commencing from the heavy connector wire 14 which leads from a terminal member 15 mounted in an insulating piece 16. The two strands are then laid in convolution and one of them terminates in the terminal piece 17 while the other terminates in the terminal piece 18, both set in the insulating piece 16. It will appear evident that the spider arms may be arranged in any suitable manner, being secured in place by means of screws 19, 19, and made to intersect wherever convenient.

In order that the expansion of the resistance wire or wires, due to the heat, may not

cause them to sag to the extent of short-circuiting convolutions, or certain parts thereof, I provide spacers 20, 20, illustrated particularly in Fig. 6. These spacers are provided with slots 21, 21, cut alternately from opposite sides to a depth a little beyond the center line, and these spacers are interposed between the spider arms, as illustrated, with the resistance wire or wires laid in the slots, 10 as shown, in order to keep them properly spaced apart. The members 20 and 9 are, of course, made of such material, as will properly resist the heat which is generated.

I claim:

15 1. In an electric heating device, two strips of insulating material, each of said strips having a lateral slot therein, said strips being laid face to face with said slots oppositely in alinement and so that the inner ends 20 of said slots register, and a heating wire 25 passing through the registering portions of said slots.

2. In an electric heating device, two strips of insulating material, each of said strips having a lateral slot therein, said strips being laid face to face with said slots oppositely in alinement and so that the inner ends 25 of said slots register, a heating wire passing

through the registering portions of said slots, and a metallic carrier for said strips. 30

3. In an electric heating device, two strips of insulating material, each of said strips having a lateral slot therein, said strips being laid face to face with said slots oppositely in alinement and so that the inner ends 35 of said slots register, a heating wire passing through the registering portions of said slots, and a metallic carrier for said strips, said carrier being of sheet material and being clamped over said strips to hold them 40 together.

4. In combination, a grid, two uncovered heating units spirally arranged therein, a pair of insulating strips laid face to face and provided with oppositely disposed alinement slots forming openings, sheet metal holders forming strips provided with flanges for clamping engagement with the strips to support the same, and spaced strips for location between adjacent supports for the 50 heating unit provided with oppositely disposed slots to receive the heating unit and space adjacent convolutions of the same.

In witness whereof, I hereunto subscribe my name this 29th day of April, A. D. 1916. 55

CLIFFORD R. WASSELL.
